UNITED STATES PATENT OFFICE.

JOSEPH A. DESJARDINS, OF NORDEGG, ALBERTA, CANADA.

CRUTCH.

1,254,993.

Specification of Letters Patent. Patented Jan. 29, 1918.

Application filed January 12, 1916. Serial No. 71,788.

To all whom it may concern:

Be it known that I, JOSEPH A. DESJARDINS, a subject of the King of Great Britain, residing at Nordegg, Alberta, Canada, have 5 invented new and useful Improvements in Crutches, of which the following is a specification.

My invention relates to improvements in crutches, one object of the invention being 10 the provision of a two membered crutch, such members being adjustably connected together, so that the crutch will be universal, and can be adjusted for use with persons of different heights.

15 A further object of this invention is the provision of an adjustable crutch, which is simple and durable in construction, and which is thoroughly practical and efficient in use.

20 In the accompanying drawings:—

Figure 1 is a side elevation of the complete crutch constructed according to and embodying my invention.

Fig. 2 is a section on line 2—2 of Fig. 1.

25 Fig. 3 is a section on line 3—3 of Fig. 1.

Fig. 4 is a view similar to Fig. 3 of a modified form of adjustable lock.

Referring to the drawings, the numeral 5 designates the two bowed members, whose 30 lower ends are connected together with the cross-bar 6, having the reduced ends 6', fitted in the lower slotted ends of the members 5, and secured therein in any desired or well known manner. The usual shoulder piece 7 is attached to the upper ends of the members 5.

The pole or rod 1, is slidably mounted 35 through the cross-bar 6, and is provided with the hand grip 2, whose reduced terminals 3, slidably fit with the opposite slots 8, formed in the members 5, the rod 1 being

provided with a plurality of equally spaced recesses or sockets 4, to receive either the pin 11 or 10', as illustrated in Figs. 3 and 4.

As shown in Fig. 3, the cross-bar 6 is provided with the chamber 9, in which slidably fits the disk 10 carried by the pin 11, which is provided with the manipulating head 12, a coiled expansion spring 13 being mounted in the chamber 9 to exert a pressure to hold 45 the pin 11 seated in one of the sockets 4, and thus hold the rod 1 from longitudinal movement, while the hand-grip 2 holds it from rotation.

In Fig. 4, the threaded bore 13' received 55 the locking screw 10', which is provided with the manipulating milled head 12'.

What I claim as new, is:

In combination, a crutch post having a handle secured at its upper end, said handle 60 being provided at its opposite ends with reduced rectangular shoulders, a pair of similarly shaped brace arms each having an intermediate straight portion and curved portions curving in opposite directions with respect to the straight portion, a shoulder rest 65 secured to the upper ends of said brace arms, the straight portions of said brace arms being provided substantially throughout their lengths with elongated rectangular grooves 70 in which the rectangular shoulders of said handle are adapted to slide relatively to said brace arms, a cross bar connecting the lower curved portions of said brace arms, and means for locking said cross bar adjustably 75 of said crutch post.

In testimony whereof I affix my signature in presence of two witnesses.

JOSEPH A. DESJARDINS.

Witnesses:

W. J. MILLICAN,
HARRY MILLICAN.
